UNITED STATES PATENT OFFICE.

FILLMORE DECKER, OF CHICAGO, ILLINOIS, ASSIGNOR TO THE CHICAGO
LAST AND DIE COMPANY, OF SAME PLACE.

DESIGN FOR A HINGE.

SPECIFICATION forming part of Design No. 30,721, dated May 9, 1899.

Application filed December 12, 1898. Serial No. 699,075. Term of patent 14 years.

To all whom it may concern:

Be it known that I, FILLMORE DECKER, a citizen of the United States, residing at Chicago, in the county of Cook and State of Illinois, have invented and produced a new and useful Design for a Hinge, of which the following is a specification, reference being had to the accompanying drawings, showing a complete hinge.

Figure 1 is a perspective view of a hinge, showing my design. Fig. 2 is a side elevation of the same, and Fig. 3 is a plan view, these three views being deemed necessary to fully illustrate my design.

The essential feature of my design consists of the hinge having the stem and joint portions shaped so that the parts thereof together form a short cylinder of substantially uniform

cross-section and provided with flattened portions on one side.

The stem A is cylindrical throughout its length and has the rectangular aperture A' to accommodate the correspondingly-shaped blade B' of the cylindrical stem B. Both stems have the holes C' to accommodate the rivet or pin C, which joins them. On one side of the hinge are the flattened rectangular portions A² and B², placed on the stems A and B, respectively.

What I claim is—

The design for a hinge substantially as shown and described.

FILLMORE DECKER.
